ABDOMINAL AND SACROILIAC SUPPORT

Filed Dec. 22, 1922

2d INVENTOR
BY SIMON C. EDMISTON
Hazard & Miller ATT'Y'S

UNITED STATES PATENT OFFICE.

SIMON C. EDMISTON, OF LOS ANGELES, CALIFORNIA.

ABDOMINAL AND SACROILIAC SUPPORT.

Application filed December 22, 1922. Serial No. 608,473.

To all whom it may concern:

Be it known that I, SIMON C. EDMISTON, a citizen of the United States, residing at Los Angeles, in the county of Los Angeles

5 and State of California, have invented new and useful Improvements in Abdominal and Sacroiliac Supports, of which the following is a specification.

This invention relates to abdominal and 10 sacroiliac supports.

It is an object of the present invention to provide an extremely simple, practical and substantial girdle-like support adapted to be readily adjusted around the lower portion 15 of the waist to fit the rear of the body and to afford a substantial support for the abdomen. Another object of the invention is to provide a support having a sufficient degree of elasticity to provide for the 20 conformation of the support to the figure without undue binding and pinching, and to provide for the accurate fitting of the support to the figure. Another object is to provide for the loosening or tightening up of the 25 device to fit a figure.

Other objects and advantages will be made manifest in the following specification of an embodiment of the invention illustrated in the accompanying drawings, wherein

30 Figure 1 is a perspective showing the device as applied over the abdomen.

Fig. 2 is a perspective showing the device as fitting across the rear of the body at and below the waist.

35 Fig. 3 is an elevation or plan of the extended device.

The support of the present invention comprises two main lateral wings or flap portions 2 and 2' connected by intermediate 40 back panel sections 3 and 3', which latter are shown as medially laced or otherwise adjustably connected together at 4 and terminating above a lower central web or strip 5, the upper portion of which is shown as 45 centrally slit as at 6 and having the side margins adjustably connected as by lacing 7 and 7' to the adjacent inner edges 2^a and 2^a' of the side flaps 2. The side flaps have upper 50 straight corner portions 2^b and 2^b' along which extend lacings 8 and 8' which connect to contiguous stiffened strips 9. These strips 9 and 9' are connected by substantial transverse elastic straps 10 and 10' to the extremities of which are secured fastening elements 11 and 11' carrying hooks and eyes or other suitable fasteners 12 and 12' which are

adapted to be closed or interlocked together when the side flaps 2 and 2' are brought around in front of the abdomen as shown in Fig. 1.

60 The side flaps 2 and 2' have downwardly and inwardly curved rear edges 2^c and 2^c' terminating in lobe-like points 2^d and 2^d'. Running upwardly from these points and embedded in the fabric of the said flaps are 65 reinforcing stays or strips 13 and 13' which curve inwardly toward the center of the support and diverge slightly at the upper portion. The central web or strip 5 is connected at its lower portion by laterally extending elastic straps 14 and 14' to the lower portions of the side flaps 2 and 2' and, therefore, when the device is applied, the lobes of the flaps and the central back strip 5 are 70 drawn snugly in across the sacroiliac. 75

To facilitate the snug fitting and adjustment of the support to the figure, the flaps 2 and 2' are provided with downwardly and outwardly curving slots 16 and 16' extending to the top edge of the support, and the 80 degree of opening of the slots is adapted to be varied by lacings 17 and 17'.

The longitudinally extending central slot 6 is shown in Fig. 2 as being provided with lacing 18 whereby the central strip may be 85 opened or closed to be adjustable to the form, and the central strip 5 is shown in Fig. 3 as provided with longitudinally extending marginally located reinforcing stays or bars 19. 90

From the above it will be seen that the support is constructed of substantial flexible elements certain of which provide for a requisite or desired degree of elasticity, and the device includes means, such as the lacings particularly above described, for enabling the snug adjustment and fitting of the various parts and portions of the device to the anatomy.

Further embodiments, modifications and 100 changes may be resorted to within the spirit of the invention as here claimed.

What is claimed is:

1. An abdominal support comprising two main lateral wings having their upper parts 105 connected by intermediate back panel sections, the panel sections being laced to the main wings and laced together, and the lower parts of the main wings being spaced apart by a lower central web, the upper part 110 of the central web being laced to the contiguous parts of the main wings and the

lower part of the central web being connected to the lower parts of the contiguous main wings by elastic straps, elastic straps laced to the outer edges of the upper parts of the main wings, and fasteners for connecting the elastic straps together.

2. In an abdominal support comprising two main lateral wings having their upper parts connected by intermediate back panel sections, the panel sections being laced to the main wings and laced together, and the lower parts of the main wings being spaced

apart by a lower central web, the upper part of the central web being laced to the contiguous parts of the main wings and the lower part of the central web being connected to the lower parts of the contiguous main wings by elastic straps, the upper part of the central web having a vertical central slit and the parts being laced together across the slit.

In testimony whereof I have signed my name to this specification.

SIMON C. EDMISTON.
